United States Patent Office

Des. 225,434
Patented Dec. 12, 1972

225,434

DINNER PLATE OR SIMILAR ARTICLE

Raymond T. Cleland, Freehold, N.J., assignor to American Home Products Corporation, New York, N.Y.

Filed Aug. 13, 1971, Ser. No. 171,805

Term of patent 14 years

Int. Cl. D7—01

U.S. Cl. D44—15

The figure is a plan view of a dinner plate of conventional configuration showing my new design.

I claim:

The ornamental design for a dinner plate or similar article, as shown and described.
